DESIGN FOR A HOSPITAL PATIENT'S
CALL LIGHT

George H. Kress, Vestal, N. Y., assignor to International Business Machines Corporation, New York, N. Y., a corporation of New York

Application July 30, 1946, Serial No. 132,115

Term of patent 14 years

(Cl. D72—1)

To all whom it may concern:

Be it known that I, George H. Kress, a citizen of the United States of America and resident of Vestal, county of Broome, State of New York, have invented a new, original, and ornamental Design for a Hospital Patient's Call Light, of which the following is a specification, reference being had to the accompanying drawing, forming part thereof.

Fig. 1 is a front elevational view of a hospital patient's call light, showing my new design.

Fig. 2 is a side view thereof.

The purpose of the shading is to indicate a contrasting appearance producing a striped effect.

I claim:

The ornamental design for a hospital patient's call light, substantially as shown and described.

GEORGE H. KRESS,
